UNITED STATES PATENT OFFICE.

HENRY GRASMUK, OF ORANGE, NEW JERSEY, ASSIGNOR TO BIPPART, GRISCOM & OSBORN, OF NEWARK, NEW JERSEY.

DESIGN FOR A BRACELET.

56,602.

Specification for Design.

Patented Nov. 16, 1920.

Application filed May 17, 1920. Serial No. 382,173. Term of patent 8½ years.

To all whom it may concern:

Be it known that I, HENRY GRASMUK, a citizen of the United States, residing at 43 Hampton Terrace, Orange, county of Essex, and State of New Jersey, have invented a new, original, and ornamental Design for a Bracelet, of which the following is a specification, reference being had to the accompanying drawing, (which is drawn upon an exaggerated scale,) forming part thereof.

The figure is an edge view of a bracelet showing my design.

I claim—

The ornamental design for a bracelet, as shown.

In testimony whereof I have hereunto set my hand.

HENRY GRASMUK.
